Inventor:

United States Patent Office.

JAMES E. CROSS, OF CHICAGO, ILLINOIS.

Letters Patent No. 67,510, dated August 6, 1867.

IMPROVEMENT IN LANTERNS.

The Schedule referred to in these Letters Patent and making part of the same.

TO ALL WHOM IT MAY CONCERN:

Be it known that I, JAMES E. CROSS, of the city of Chicago, in the State of Illinois, have invented a certain new and useful Improvement on Lanterns; and I do hereby declare that the following is a full, clear, and exact description of the same, reference being had to the accompanying drawings, and to the letters and marks thereon, which said drawings form part of this specification, and represent a lantern and several of the parts thereof, with my improvement attached thereto.

The object of this invention is to produce a lantern so constructed that an oil-cup or lamp or a candle may be used therein without having to take off any piece or part for the fitting in of another and different piece or part, and of producing a cheap, durable, and useful lantern.

The guard-bars or rods *a*, as shown by vertical section of the lantern in fig. 1, instead of being soldered or otherwise secured to the sides of the dome *b*, pass through the dome, each rod or bar being one continuous piece from the bottom guard-bar *c* on one side to the other, *d*. Each bar or rod of the guard then passing through the dome strengthens the dome and the guard, and, as a whole, the guard can be made cheaper and better than when the upper ends of the bars or rods are secured to the sides of the dome. The lantern here illustrated has the dome and guard attached to each other, and are removable as one piece from the bottom part of the lantern. The oil-cup *e* has attached to its bottom plate a socket, *f*, in which may be fitted a candle or a lamp, the socket being stayed by a brace, *g*. The bottom plate is extended out so as to form a flange, *h*, from the periphery of which pieces are cut out, leaving spaces, *i*. To the bottom of the lantern are affixed small plates, *j*, that constitute catches, so that when the spaces *i* of the flange *h* are in line with the catches *j* the flange *h* can be placed in contact with the plate of the bottom of the lantern, and when turned to a slight degree, so that the flange *h* passes over the catches *j*, the oil-cup will be held in position or the socket be held inward and in position, just as the one or the other may be in use. The spaces *i* and the catches *j* therefore constitute the means for holding either side of the flange *h* in contact with the bottom plate of the lantern. It will be readily seen that either the oil-cup or the socket may be the upward or downward piece or part, as may be required.

What I claim as my invention, and desire to secure by Letters Patent, is—

1. The construction of the oil-cup with the socket, so that it may be used for oil or with a candle, substantially as herein recited.
2. I claim the combination of the space *i* of the flange *h* and the catches *j* for attaching the oil-cup to the bottom of the lantern.

This specification signed this 28th day of January, 1867.

JAMES E. CROSS.
